UNITED STATES PATENT OFFICE.

EDWARD AUSTIN HERR, OF WASHINGTON, DISTRICT OF COLUMBIA.

COMBINED COLLAR-BUTTON AND NECKTIE-FASTENER.

SPECIFICATION forming part of Letters Patent No. 729,582, dated June 2, 1903.

Application filed June 18, 1902. Serial No. 112,222. (No model.)

To all whom it may concern:

Be it known that I, EDWARD AUSTIN HERR, a citizen of the United States, residing at Washington, in the District of Columbia, have 5 invented certain new and useful Improvements in a Combined Collar-Button and Necktie-Fastener, of which the following is a specification.

My invention relates to collar-buttons and 10 scarf-holders, and has for its object to provide a simple, cheap, and effective device which is capable of use both for a collar-button and as a scarf-holder; and to these ends my invention consists in the various features of construction and arrangement of parts, having 15 the general mode of operation substantially as hereinafter more fully set forth.

Referring to the accompanying drawings, 20 Figure 1 is a side view, enlarged, of a device embodying my invention. Fig. 2 is a vertical partial section. Fig. 3 is a partial vertical section showing the parts in different relations. Fig. 4 is a transverse section showing the under side of the head. Fig. 5 is a 25 bottom plan showing the rim of the top plate cut away or notched and the spring-plate. Fig. 6 is a bottom plan view of the hinged plate.

Referring to the drawings, wherein I have 30 illustrated the preferred embodiment of my invention, 1 represents a shank or pillar, which is shown as made of a rigid piece of material the lower portion of which is spun out or otherwise extended to form means for securing it to the base, as shown, and it is 35 hollowed or recessed, as at 2, and provided with an extended flange 3. The upper end of the shank or pillar is extended and shaped to form a flat face or platform 5, having relatively sharp corners 5^a extending beyond the 40 body of the shank at two opposite sides thereof, the sides being inclined from the top of the platform toward the body of the shank, as shown, and arranged on the shank below the platform are the ears 6 6, to which the 45 head of the device is connected or hinged, as hereinafter specified.

The head comprises a top plate 7, the rim or edge of which is spun or curved downward, as at 8, and mounted in the top plate is a 50 spring-plate 9, shown in the form of a disk, and outside this spring-plate is a hinge-plate 10, and both the spring-plate and hinge-plate

are conveniently held in position by the spun or curved edge of the top plate.

The hinge-plate 10 is provided with two upset portions 11 11, constructed and arranged to embrace the ears 6 6 of the shank and form a hinge, and the hinge-plate 10 is preferably made with a slot 12, through which slot projects the shank and which slot extends to both 55 sides of the shank. The edges of the hinge-plate, between the two portions thereof and at the ends of the slot 12, are depressed, as indicated at 10^a, to practically form a continuation of the slot 12. The edge or rim of 60 the top plate 7 is cut away or notched, as at 13 13, on opposite sides in alignment with the slot 12 and depressed portions 10^a.

In order to constitute a scarf-holder, the 65 face of the top plate is provided with one or more pins or hooks 14 14, two being shown in the drawings, and these are secured to the plate in any suitable manner, as by extending them through perforations in the plate and upsetting or heading the pins on the under side, or they may be soldered or otherwise secured in position, so that they project 70 outward from the plate and are bent to extend substantially parallel with the outer face of the plate, substantially as indicated 75 in the drawings. These pins or hooks are arranged preferably away from the center of the plate and adjacent one edge of the same, as indicated in the drawings.

The base of the button may be of any desired 80 construction and, as shown, comprises a plate 15, the edge of which is spun up or curved to secure the flange or flaring end 3 of the shank in position. It is not absolutely necessary to provide this base-plate, as the 85 lower portion of the shank can be formed or shaped so as to practically constitute a base for the button; but I prefer to provide the base-plate, arranged substantially as indicated above.

Such being the general construction of my 90 device it will be seen that it provides a simple and substantial combination of parts that can readily be made, and the head is so mounted that it is securely held in its normal position by means of the spring-plate 95 resting on the flat face or platform 5, which furnishes a substantial support therefor, and when it is desired to tilt the head to one side 100

or the other it can be rocked over the projection 5^a to the position shown in Fig. 3, for instance, and then the projection tends to hold the head in this position, as it is above 5 the ears 6 6, and holds the head under spring tension in this position. When the head is so tilted, the shank comes into the slot 12 and enters one of the notches 13 in the rim of the head, so that the head can be turned or tilted 10 to one side or the other into a position substantially parallel with the shank, as best seen in Fig. 3. There are several advantages due to this construction and arrangement of parts, among which may be mentioned the 15 fact that there is no danger of tilting the head when it is being inserted in the button-hole of the shirt or collar or other article to which it is to be applied, and when it is desired to withdraw the head, the head being 20 tilted to the side opposite that shown in Fig. 3, the notch permits the rim or edge of the head to extend over and practically embrace the edge or sides of the shank, so that there is no danger of the head catching on the edges 25 of the buttonhole or the material from which it is being withdrawn. It is manifest that with the hooks 14 it is necessary that the head may be tilted to either side, so that the hooks will not catch on the buttonhole in 30 either inserting or withdrawing the head. The shape of the platform, especially in connection with the spring-plate and the arrangement before described, is such that it tends to hold the head in either of three positions—³⁵ that is, in its normal position, as indicated in Figs. 1 and 2, or when tilted to either side, it being shown as tilted to one side, as in Fig. 3—and in all three of these positions it will be seen that it is under spring tension. 40 The notches in the rim of the head and the recess or cut-away portions of the hinge-plate also perform an important function in permitting the head to be tilted, so as to be practically parallel with the axis of the shank, to 45 facilitate its insertion and withdrawal in the manner above indicated.

What I claim is—

1. A collar-button comprising a shank having a flat face or platform at its upper end 50 extending beyond the body of the shank on two sides thereof and provided with ears below the platform, and a head hinged to said ears and constructed and arranged to bear with spring-pressure upon the platform, substantially as described.

2. A collar-button comprising a shank and a head pivotally connected thereto, the head being provided with notches at its edges adapted to engage the shank when the head 60 is brought into parallelism with the shank, substantially as described.

3. A collar-button comprising a shank and

a head pivotally connected thereto, the head being provided with notches adapted to engage the shank when the head is brought 65 into parallelism with the shank, and a hinge-plate, said hinge-plate being recessed to receive the shank, substantially as described.

4. A collar-button comprising a shank and a head pivotally connected thereto, the head 70 being provided with notches adapted to engage the shank when the head is brought into parallelism with the shank, and a hinge-plate being provided with a slot in its central portion and depressed portions at its edges, 75 whereby when the head is brought into parallelism with the shank, the shank will rest in one of the notches of the head, the slot in the hinge-plate and one of the depressed portions thereof, substantially as described. 80

5. A collar-button comprising a shank having a flat face or platform at its upper end, ears arranged below the platform, and a head comprising a face-plate, a spring-plate and a hinge-plate secured together, the hinge-plate 85 being recessed and the face-plate being notched to receive the shank when the head is tilted, substantially as described.

6. A combined collar-button and scarf-holder comprising a shank, and a head pivotally connected thereto and adapted to move into three positions with relation to the shank, said head being provided with hooks projecting from its face on one side of its pivotal point and extending toward the latter, substantially as described. 90

7. A combined collar-button and scarf-holder comprising a shank having a platform at its upper end, and a head pivotally mounted on said shank, and adapted to be moved 100 into three positions with relation to the shank, said head consisting of a face-plate, hooks mounted thereon, a spring-plate and a hinge-plate secured together, substantially as described. 105

8. A combined collar-button and scarf-holder comprising a shank having a platform at its upper end and ears below the platform and a head pivotally mounted on said shank and adapted to be tilted in three positions 110 and held under spring-pressure in each position, the head consisting of a face-plate having a notched rim, hooks mounted on the face-plate at one side of its pivotal center, a spring-plate and a hinge-plate provided with 115 a slot and with upset portions to engage the ears of the shank, substantially as described.

In testimony whereof I have signed my name to this specification in the presence of two subscribing witnesses.

EDWARD AUSTIN HERR.
